Samuel Wilkeson
The Schedule referred to in this letter follows and making part of
the same containing a description in the words of the said Samuel
Wilkeson himself of his improvement in the Plough.

To all to whom these presents shall come, Be it known that I, Samuel
Wilkeson of Gettysburg in the County of Adams and State of Pennsylvania
have invented and applied improvement in the Plough the im-
provement consisting in placing a Roller under the beam near the an-
tler of the Plough in or near a perpendicular position. The Roller may
be made plain, ridged, grooved or otherwise, the use of the Roller is to pre-
vent the plough from chocking by rolling of the vegetable matter that
naturally collects under the beam.
